UNITED STATES PATENT OFFICE

LYDIA LAMPERT, OF CHICAGO, ILLINOIS, ASSIGNOR TO UNIVERSAL FORM CLAMP CO.,
OF CHICAGO, ILLINOIS, A CORPORATION OF ILLINOIS

BAR SUPPORT AND SPACER

Application filed February 21, 1931. Serial No. 517,514.

The main objects of this invention are to provide an improved bar support and spacer for use in supporting reinforcing bars used in concrete construction work and to space them the desired distance from one another and from the forms; to provide an improved form of bar supporting chair; and to provide an improved bar support and spacer of simple construction which requires a minimum amount of hand labor in the assembly of its parts.

An illustrative embodiment of this invention is shown in the accompanying drawings, wherein:—

15 Figure 1 is a fragmentary perspective of a bar support and spacer, showing two of the improved chairs secured to a spacing rod.

Fig. 2 is a side elevation of the same, showing also two reinforcing bars in section as they appear when seated on the chairs; the dotted lines representing the reinforcing bars prior to being forced downwardly into the chair seats.

Fig. 3 is a vertical section, taken on the line 3—3 of Fig. 2.

Fig. 4 is a top plan of the portion shown in Fig. 3; but shows the reinforcing bar in dotted outline.

In the form shown, the reinforcing system 30 involves the use of the customary reinforcing bars 1 disposed horizontally in substantially parallel spaced relation above a false-work, not shown.

The improved bar support and spacer comprises a plurality of supporting chairs 2, which are spot welded or otherwise rigidly secured to a spacing rod 3, whereby the chairs are permanently spaced the desired distance from one another. The chairs 2 and 40 spacing rod 3 are made of wire of a gauge which will insure the necessary rigidity but still permit the chairs to be bent to the desired shape.

In the form shown, each of the supporting 45 chairs 2 comprises a single piece of wire hav-

ing its central portion doubled upon itself to form a vertical intermediate leg 4 located below the spacing rod. The upper ends of the leg 4 form a pair of arms 5 which are bent to define a substantially U-shaped seat 50 located in the vertical plane of the intermediate leg and having its base part located above the spacing rod 3. With this improved construction, the entire weight of the reinforcing bars is carried by the chairs. If the bars were carried by the spacing rod, the strain might rupture the welded joints. In order to restrict the throat of the U-shaped seat, the arms 5 are crimped inwardly, as shown at 6.

The upper ends of the arms 5 are bent to form a pair of end legs 7, which diverge downwardly relative to the vertical plane of the seat, so as to secure the chairs against tipping.

In operation, the improved devices are placed on the falsework with the spacing rods 3 disposed substantially parallel to one another at the desired intervals. The reinforcing bars are then placed in the throats 70 of the seats and are pressed downwardly into their chairs.

Although but one specific embodiment of this invention has been herein shown and described, it will be understood that numerous 75 details of the construction shown may be altered or omitted without departing from the spirit of this invention as defined by the following claims.

I claim:

1. A reinforcing bar chair comprising a single piece of wire having its central portion doubled upon itself to form a vertical intermediate leg, the upper ends of said leg 85 forming a pair of arms bent to define a substantially U-shaped seat located in the vertical plane of said intermediate leg, the upper ends of said arms being bent downwardly and outwardly to form a pair of end legs 90.

diverging downwardly on respectively opposite sides of said vertical plane.

2. A reinforcing bar support and spacer comprising a spacing rod and a plurality of chairs welded thereto, each of said chairs comprising a single piece of wire having its central portion doubled upon itself to form a vertical intermediate leg welded to said rod, the upper ends of said leg forming a pair of arms bent to define a substantially U-shaped seat located in the vertical plane of said intermediate leg, the upper ends of said arms being bent downwardly to form a pair of end legs diverging downwardly on respectively opposite sides of said spacing rod and of said vertical plane.

Signed at Chicago this 19th day of February, 1931.

LYDIA LAMPERT.
